UNITED STATES PATENT OFFICE

133,642

DESIGN FOR A RELAXING CHAIR

Rose Mints, Los Angeles, Calif.

Application October 9, 1941, Serial No. 103,694

Term of patent 3½ years

To all whom it may concern:

Be it known that I, Rose Mints, a citizen of the United States, residing at Los Angeles, in the county of Los Angeles and State of California, have invented a new, original, and ornamental Design for a Relaxing Chair, of which the following is a specification, reference being had to the accompanying drawing, forming part thereof.

The side of the chair opposite to that shown in Figure 1 is similar thereto.

I claim:

The ornamental design for a relaxing chair, as shown and described.

ROSE MINTS.
